UNITED STATES PATENT OFFICE.

WILLIAM S. MENDEN, OF BROOKLYN, NEW YORK, ASSIGNOR TO MEGOSIN COMPANY, INC., A CORPORATION OF NEW YORK.

SYSTEM OF CONTROLLING RAILWAY-CARS.

1,209,469.

Specification of Letters Patent. Patented Dec. 19, 1916.

Application filed June 17, 1914. Serial No. 845,615.

To all whom it may concern:

Be it known that I, WILLIAM S. MENDEN, a citizen of the United States, and resident of the borough of Brooklyn, in the county 5 of Kings and State of New York, have invented certain new and useful Improvements in Systems of Controlling Railway-Cars, of which the following is a full and clear specification.

10 This invention relates to a system of controlling railway cars and has for its primary object to provide an improved system for that class of systems which upon becoming active automatically bring the cars 15 to rest and require a voluntary movement on the part of an operator for reestablishing the normal conditions under which the cars are propelled.

One of the objects of my invention is to 20 provide improved emergency control apparatus for rapid transit cars, embodying means depending upon the movement of the cars for holding car-stopping means inoperative until automatically operated by an 25 outside agency and in which in the event of said holding means becoming inoperative from any cause, the automatic stopping of the cars will not be interfered with. Furthermore, a slight volitional movement on 30 the part of the motorman makes it possible to reestablish normal running conditions whether the emergency control apparatus is operable or not.

Another object is to provide an improved 35 system which calls for a volitional movement on the part of an operator but which can be transformed into a full automatic system at will. A further object is to provide an improved co-operative arrangement 40 of the emergency apparatus which automatically sets the maximum and minimum speed limits.

Other and further objects will appear in 45 the specification and claims, reference being had to the accompanying drawings in which,—

Figure 1 is a diagrammatic view of the 50 circuits on a single car, according to one embodiment of my invention, certain of the instrumentalities being shown in section; Fig. 2 is a similar diagram showing this embodiment applied to a train of cars, said instrumentalities being shown in elevation;

Fig. 3 is a similar diagram for a train showing an embodiment of the invention.

55

In the embodiment shown in Figs. 1 and 2, a brake control valve 1 is connected to the train pipe 2 on one side and is provided with an outlet pipe 3 on the other side, adapting it to discharge into the air thereby. 60 Said valve is provided with a pressure chamber 4 which is in continuously open communication with an upper chamber 5 by means of a channel 6. A valve seat 7 is suitably arranged to be closed by a valve 8 which has a valve stem 9 slidably supported in the cap 10 of the valve. Interposed between the valve 8 and the cap 10 is a spring 11 which co-operates with the air pressure in the chamber 5 to normally retain 70 the valve 8 against the seat 7 when the vehicle is moving. A pipe 12 serves to connect the chamber 5 with a chamber 13 of a housing 14, within which is mounted an electro-responsive device in the form of a 75 magnetic coil 15 which when energized draws a plunger 16 downwardly. Said plunger is reciprocably mounted within a sleeve 17, its lower end being adapted to open and shut an opening 18 through which 80 the chamber 13 communicates with a bleed channel 19 at such times as the plunger 16 may be raised by a spring 20 when the magnet 15 is deenergized. Said spring is interposed between the bottom wall of chamber 85 13 and a spider 21 which is connected to the lower end of the plunger 16 by means of a reduced neck 22. Plunger 16 carries an armature 23 which reciprocates in cylinder 24.

Projecting upwardly from the plunger 16 90 is a stem 25 which carries spaced contact bridges 26 and 27, the former of these being adapted to close a gap in a motive power circuit control wire 28. The contact 27 is adapted to close a gap in a relay circuit, to 95 be presently referred to. For initially energizing the coil 15, the positive line wire of the car is connected by a wire 30 with a master reset line 32, said wire 30 being provided with a switch 31 which is adapted to 100 open and close a gap therein. Said switch 31 is preferably held in open position by a spring 31^a. If desired, however, said spring may be removed to permit the switch 31 to 105 be kept closed in order to render the system fully automatic as will be understood.

Leading from the reset line 32 is a wire 33 which connects with the coil 15, being provided with a gap between the spaced contacts 34 which normally retain an open circuit while the car is running. Leading from the coil 15 is a wire 34 which is grounded in the negative line wire 35, being provided with gaps between spaced contacts 36 and 37. These gaps are normally retained closed by contact bars 38 and 39 which are pivoted respectively at 40 and 41 being provided with depending arms 42 and 43 which are adapted to be engaged by any suitable means disposed along the route of the cars. Mounted on the axle 44 of wheels 45 (one only being shown) is a gear 46 which meshes with a pinion 47 for driving the dynamo 48, said dynamo being grounded through the line 49. A circuit including said dynamo is completed through the ground line 49, another ground line 50 which connects with one end of a solenoid 51, the other end of said solenoid being connected by a line 52 with the dynamo 48. When the car is running therefore, solenoid 51 acts upon the plunger 53 to retain a bridge contact 54 in raised position. When, however, the car is at rest bridge contact 54 drops upon the spaced contacts 34 and thus completes a circuit from positive line 29, connection 30, reset line 32, line 33, coil 15 and ground line 34, the contact bars 38 and 39 being then in position to close the gaps 36 and 37. Under these conditions, the operator by closing the switch 31 energizes the coil 15 and draws the plunger 16 downwardly, the armature 23 being attracted by the magnetized sleeve 17. At the same time, the contact 26 closes the gap in the main car control line 28, thus giving the operator the power to accelerate the car. Simultaneously, the contact 27 closes a gap in the line 55 which leads from the positive line 29 to one of the contacts 56 which forms said gap, the other of said contacts being connected to the wire 33. In this way, if the coil has been initially energized, it is maintained energized by the current flowing from positive line 29 through wire 55, contact 27, line 33, coil 15 and ground line 34 to negative line 35. As soon as the car is accelerated, the bridge contact 54 is raised and breaks the initial energizing circuit, until the car again comes to rest, so that whenever either or both of the contact bars 38 and 39 are operated to break what might be termed the permanent energizing circuit, of the coil 15, an event which would be occasioned by an emergency, plunger 16 would be released to move upwardly, with the result that contact 26 would break the main power control line 28 while at the same time the release of the air from chamber 5 of the emergency braking device would cause an emergency application of the

brakes. During this time, it would be impossible for the operator to reestablish either the initial energizing circuit for the coil 15 or the main control circuit or to release the brakes for the reason that the bridge contact 54 would be retained in raised position until the cars came to rest. By reference to Fig. 2, the application of this system to a train will be seen at a glance, the parts just described being duplicated in each car of the train. It will be seen that the master reset line 32 extends throughout the length of the train, together with the positive and negative lines. It will be apparent therefore, that whenever the train is at rest, all of the bridge contacts 54 being in lowered position, the coil 15 on every car will be energized whenever anyone of the switches 31 is closed. In consequence, all of the main power control lines 28 for the different cars will be closed simultaneously, thus placing all of the cars under the control of the operator. At the same time, all of the permanent energizing circuits for the coils 15 will be simultaneously completed. Let it be supposed now for example that a dynamo 48 becomes inoperative for any reason. The consequence would be that the bridge contact 54 would remain at all times in position to bridge the gap between contacts 34. In consequence should the switch 31 be retained normally closed, whenever an emergency operation occurred the reset line would act immediately to reestablish normal working conditions. Should the car be operated singly, the object of the system would be that whenever the car is operated singly, the switch 31 may be left open so that the reset could only be accomplished by a voluntary action on the part of the operator. Thus the car would come to a stop from an emergency operation. In a train of cars, on the other hand, it will be understood that with the switch 31 in closed position, if but a single dynamo 48 be in active operation, the emergency train stopping device will act automatically to bring the train to a rest.

Referring now to the embodiment shown in Fig. 3, the emergency control apparatus is substantially similar in construction to that already pointed out in connection with the embodiment shown in Figs. 1 and 2. Each car in a train has an emergency brake-applying valve within a housing 1' and a magnetic controlling valve in a housing 14', said housings being connected by pipes 12 and adapted to operate in the same manner. When the train is at rest, magnet in housing 14' is initially energized by the following circuit: plus line 29', connection 30', reset line 32', wire 33', contacts 34', bridge contact 57 pivoted at 58 which is normally held in raised position by a spring 59, wire 60, spaced contacts 61 closed by a sliding bridge 130

contact 62 which is carried by the stem of the plunger within the housing 14' and which is then in raised position, wire 63 and wire 64 which is grounded and provided with gaps normally closed by contact bars 65 and 66, said contact bars being adapted to be operated in emergencies as pointed out in the other embodiment. As soon as the magnet in housing 14' is energized, sliding bridge contact 62 is drawn down to close the circuit from positive line 29', which includes wire 67, sliding bridge contact 62, wire 63 and wire 64 to ground, thus completing the so-called permanent circuit. In this embodiment, the synchronizing line wire 68 is provided which extends throughout the train. When the emergency is operated and the coil in housing 14' is deenergized, a contact 69 is permitted to rise for closing a circuit including positive line 29', wire 67, wire 70, synchronizing line 68, wire 71, solenoid within housing 72, wire 73, and negative line wire 35'. By energizing said coil, the contact 74 is drawn downwardly to break the main power control line 75. The solenoid within housing 72 is also adapted when energized to apply the brakes by releasing air from a pipe 76. It will thus be seen that whenever the emergency device is operated, the automatic brake-applying device on the car is maintained in action until the car comes to rest and in addition thereto, the main power circuits on every car are broken by the retraction of contacts 74, the synchronizing line 68 in connection with positive and negative lines 29' and 35' being adapted to reproduce this action on every car of the train.

Means for automatically operating the speed control device within the housing 72 independently of the emergency car-stopping device are provided as follows: A dynamo 77 having field winding 78 is driven by the running gear of the car and is grounded through line 79. A line 80 connects with the solenoid coil 81, the other end of said coil being connected by a wire 82 with the resistance 83, a plurality of branches 84, 85, and 86 being provided, whereby any or all of the resistances 83 can be thrown out of circuit by means of a contact plunger 87 which is automatically raised during different zones of travel to predetermined, different speed limits for that zone. Whenever the solenoid 81 is energized, contact 88 is raised to close the gap in a circuit including a battery 91, wire 92, wire 93, synchronizing line 68, wire 71, coil in housing 72, wire 73 and negative line wire 35'. The solenoid 81 is of such construction that the energy therein is not sufficient to raise the contact 88 until such time as the speed of the train generates sufficient power in the generator 77 to effect this displacement, the speed required of the train corresponding to the

maximum speed limit. Whenever this occurs, it will be understood that the relations of the parts are such as will cause the operation of the speed controls on every car in the train.

Obviously, various changes could be made in the arrangement of circuits and in the constructions of the several instrumentalities employed without departing from the broad spirit of my invention which resides in the combinations of elements set forth in the appended claims.

I claim:

1. In a system of operating railway cars, cars, an instrumentality on each car, adapted when operated to bring the cars to rest, a circuit for initially energizing said instrumentality, a circuit breaker in said circuit, a circuit for holding said instrumentality energized, and means depending on the movement of said cars for holding said circuit breaker in open position, said circuit including a conductor provided with a normally open switch.

2. In a system of operating railway cars, cars, an instrumentality on each car, adapted when operated to bring the cars to rest, a circuit for initially energizing said instrumentality, a circuit breaker in said circuit, depending on the movement of said cars for holding said circuit breaker in open position, said circuit including a conductor provided with a normally open switch, a circuit for holding said instrumentality energized, and circuits controlled by said switch for simultaneously resetting the instrumentalities on all of said cars.

3. In a system of operating cars, a car, an emergency device for bringing the car to rest, an energizing circuit for said device provided with two positive branches, each of said branches being provided with a brake adapted to be controlled by said device, one of said branches being provided with an additional circuit breaker, and means energized by said car in movement for normally retaining said additional circuit breaker in circuit breaking position.

4. In a train of cars, a motive power control circuit extending through the several cars of said train, said circuit embodying a circuit breaker for each car, an emergency device on one of said cars for bringing said train to rest, means operated by said emergency device for operating all of said circuit breakers in the train, and brake-applying means operatively connected to said circuit-breaker operating means.

5. In a car, an emergency device adapted when actuated to bring said car to rest, an energizing circuit for controlling the operation of said device, said circuit being provided with spaced contacts, a movable contact normally bridging said contacts when the car is at rest, a speed control in-

- strumentality, an energizing circuit therefor embodying spaced contacts, a bridge contact adapted to bridge said contacts in the speed control energizing circuit, a solenoid, a plunger in said solenoid connected to the last mentioned bridge contact, said plunger being normally held in position to remove the connected bridge contact to circuit breaking position, and a dynamo driven by the movement of said car and connected up to said solenoid, said plunger being adapted to be shifted by said solenoid under a predetermined speed of said car, the first said movable contact being suitably disposed with respect to said plunger to be attracted thereby to break the emergency control circuit when the car is in motion.
6. In a train of cars, plus and minus line wires extending throughout the length of the train, a synchronizing line wire also extending throughout the length of the train, a speed control instrumentality on each car connected to said minus and synchronizing lines, a source of power on each car having its poles connected respectively to said synchronizing line and minus line, a circuit breaker in circuit with said source of power and speed control, and means on each car and depending on the speed of the train for actuating said circuit-breaker, the actuation of the circuit breaker on any one of said cars, being adapted to complete energizing circuits which include the speed control instrumentalities on every car in the train.
7. In a train of cars, plus and minus line wires extending throughout the length of the train, a synchronizing line wire also extending throughout the length of the train, a speed control instrumentality on each car connected to said minus and synchronizing lines, a source of power on each car having one pole connected to said minus line wire, a pair of spaced contacts on each car connected respectively to said synchronizing line and the other pole of said power source, a bridge contact adapted to bridge said spaced contacts, means on each car and depending on the speed of the train for moving said bridge contact, the actuation of any one of said bridge contacts being thus adapted to complete energizing circuits which include the speed control instrumentalities on every car in the train, an emergency device on each car adapted when operated to bring the train to rest, an energizing circuit therefor embodying spaced contacts, and means for bridging the last mentioned spaced contacts when the train is at rest.
8. In a train of cars, plus and minus line wires extending throughout the length of the train, a synchronizing line wire also extending throughout the length of the train, a speed control instrumentality on each car connected to said minus and synchronizing lines, a source of power on each car having

one pole connected to said minus line wire, a pair of spaced contacts on each car connected respectively to said synchronizing line and the other pole of said power source, a bridge contact adapted to bridge said spaced contacts, means on each car and depending on the speed of the train for moving said bridge contact, the actuation of any one of said bridge contacts being thus adapted to complete energizing circuits which include the speed control instrumentalities on every car in the train, an emergency device on each car adapted when operated to bring the train to rest, an energizing circuit therefor embodying spaced contacts, and means for bridging the last mentioned spaced contacts when the train is at rest, the last said means comprising a movably mounted contact bar under normal tendency to bridge said last mentioned spaced contacts and adapted to be displaced by the magnetism in said plunger when the solenoid carries a current.

9. In a system of operating railway cars, the combination of a train of cars, positive, negative, synchronizing, and reset line wires extending through said train, a connection between said reset line and said positive line provided with a switch, a speed control instrumentality connected up between said negative and synchronizing lines, a source of power, a connection between said synchronizing and negative lines including said source of power in series with said speed control instrumentality, said connection being provided with spaced contacts, a normally open circuit breaker for said contacts, an electro-responsive device for operating said circuit breaker, a dynamo driven by the running gear of each car and connected to said electro-responsive device, an emergency train-stopping device, a connection between said positive line and said negative line, said connection including said emergency device and a pair of spaced contacts, a conductor movable by said emergency device for bridging the last said contacts and a conductor for connecting said reset line to said emergency device.

10. In a system of operating railway cars, the combination of a train of cars, positive, negative, synchronizing, and reset line wires extending through said train, a connection between said reset line and said positive line provided with a switch, a speed control instrumentality connected up between said negative and synchronizing lines, a source of power, a connection between said synchronizing and negative lines including said source of power in series with said speed control instrumentality, said connection being provided with spaced contacts, a normally open circuit breaker for said contacts, an electro-responsive device for operating said circuit breaker, a dynamo driven by

- the running gear of each car, and connected to said electro-responsive device, an emergency train-stopping device, a connection between said positive line and said negative line, said connection including said emergency device and a pair of spaced contacts, a conductor movable by said emergency device for bridging the last said contacts and a conductor for connecting said reset line to said emergency device, the last said conductor including a switch operated by said electro-responsive device.
11. In a system of operating railway cars, the combination of a train of cars, positive, negative, synchronizing, and reset line wires extending through said train, a connection between said reset line and said positive line provided with a switch, a speed control instrumentality connected up between said negative and synchronizing lines, a source of power, a connection between said synchronizing and negative lines including said source of power in series with said speed control instrumentality, said connection being provided with spaced contacts, a normally open circuit breaker for said contacts, an electro-responsive device for operating said circuit-breaker, a dynamo driven by the running gear of each car, and connected to said electro-responsive device, an emergency train-stopping device, a connection between said positive line and said negative line, said connection including said emergency device and a pair of spaced contacts, a conductor movable by said emergency device for bridging the last said contacts and a conductor for connecting said reset line to said emergency device, the last said conductor including spaced contacts suitably disposed to be closed by the conductor which is moved by said emergency device.
12. In a system of operating railway cars, the combination of a train of cars, positive, negative, synchronizing, and reset line wires extending through said train, a connection between said reset line and said positive line provided with a switch, a speed control instrumentality connected up between said negative and synchronizing lines, a source of power, a connection between said synchronizing and negative lines including said source of power in series with said speed control instrumentality, said connection being provided with spaced contacts, a normally open circuit breaker for said contacts, an electro-responsive device for operating said circuit breaker, a dynamo driven by the running gear of each car, and connected to said electro-responsive device, an emergency train-stopping device, a connection between said positive line and said negative line, said connection including said emergency device and a pair of spaced contacts, a conductor movable by said emergency device for bridging the last said contacts and a conductor for connecting said reset line to said emergency device, the last said conductor including spaced contacts suitably disposed to be closed by the conductor which is moved by said emergency device.
13. In a system of operating railway cars, the combination with a car, of a speed control instrumentality, an emergency device adapted when operated to bring the car to rest, an energizing circuit for said speed control embodying a circuit breaker operated by said emergency device, a circuit for energizing said emergency device provided with a circuit breaker, means depending on the movement of the cars for holding one of said circuit breakers open, and a manually operated switch in said emergency device-energizing circuit.
14. In a system of operating railway cars, the combination of a train of cars, positive and negative line wires extending through said cars, a synchronizing line also extending through said cars, an emergency car-stopping device on each car connected in circuit between said positive and negative line wires, a circuit breaker in series therewith, means for closing said circuit breaker embodying an element depending upon the train being at rest, and a normally open switch in circuit with said closing means for said circuit breaker, said closing means including another circuit breaker directly under the control of said emergency device.
15. In a system of operating railway cars, the combination of a train of cars, positive and negative line wires, extending through said cars, a synchronizing line also extending through said cars, an emergency car-stopping device on each car connected in circuit between said positive and negative line wires, a circuit breaker in series therewith, means for closing said circuit breaker embodying an element depending upon the train being at rest, and a normally open switch in circuit with said closing means for said circuit breaker, said closing means including another circuit breaker directly under the control of said emergency device, said normally open switch being connected up in a conductor connecting the positive line with the last said circuit breaker.
16. In a system of controlling railway cars, the combination of a train of cars, positive, negative, synchronizing and reset lines extending throughout the length of said train, an emergency car-stopping device on each car, a circuit including two pairs of spaced contacts, a bridge-contact for the gap between each pair of contacts, a solenoid for setting said device, said solenoid being adapted when energized to hold one of said bridge-contacts in open position, a solenoid

for holding the other bridge-contact in open position, and a dynamo which is operated while the train is in motion, said dynamo being connected up with the second mentioned solenoid.

17. In a system of controlling railway cars, the combination of a train of cars, positive, negative, synchronizing and reset lines extending throughout the length of said train, an emergency car-stopping device on each car, a circuit including two pairs of spaced contacts, a bridge contact for the gap between each pair of contacts, a solenoid for setting said device and a switch other than said bridge contacts, said solenoid being adapted when energized to hold one of said bridge contacts in open position, a solenoid for holding the other bridge contact in open position, a dynamo which is operated while the train is in motion, said dynamo being connected up with the second mentioned solenoid, a connection provided with a gap connecting said solenoid to the positive line independently of the above mentioned bridge contacts, a bridge contact for the last mentioned gap adapted to be held in open position by said solenoid when energized and means adapted to be operated from without the train for breaking the solenoid circuit while the train is moving, said switch being interposed between said reset and positive lines to control the energization of the solenoids on every car when the train is at rest.
18. In a system of controlling railway cars, the combination of a train of cars, positive, negative, synchronizing and reset lines extending throughout the length of said train, an emergency car-stopping device on each car, a circuit including two pairs of spaced contacts, a bridge-contact for the gap between each pair of contacts, a solenoid for setting said device and a switch other than said bridge contacts, said solenoid being adapted when energized to hold one of said bridge contacts in open position, a solenoid for holding the other bridge contact in open position, a dynamo which is operated while the train is in motion, said dynamo being connected up with the second mentioned solenoid, a connection provided with a gap connecting said solenoid to the positive line independently of the above mentioned bridge contacts, a bridge contact

for the last mentioned gap adapted to be held in open position by said solenoid when energized, means adapted to be operated from without the train for breaking the solenoid circuit while the train is moving, said switch being interposed between said reset and positive lines to control the energization of the solenoids on every car when the train is at rest, a speed control instrumentality, and a circuit for operating the same provided with spaced contacts and a bridge contact for bridging said contacts under the control of the solenoid energized by said dynamo.

19. In a system of controlling railway cars, the combination of a train of cars, positive, negative, synchronizing and reset lines extending throughout the length of said train, an emergency car-stopping device on each car, a circuit including two pairs of spaced contacts, a bridge-contact for the gap between each pair of contacts, a solenoid for setting said device, and a switch, said solenoid being adapted when energized to hold one of said bridge contacts in open position, a solenoid for holding the other bridge contact in open position, a dynamo which is operated while the train is in motion, said dynamo being connected up with the second mentioned solenoid, a connection provided with a gap connecting said solenoid to the positive line independently of the above mentioned bridge contacts, a bridge contact for the last mentioned gap adapted to be held in open position by said solenoid when energized, means adapted to be operated from without the train for breaking the solenoid circuit while the train is moving, said switch being interposed between said reset and positive lines to control the energization of the solenoids on every car when the train is at rest, a speed control instrumentality, and a circuit for operating the same provided with spaced contacts and a bridge contact for bridging said contacts under the control of the solenoid energized by said dynamo, said speed control instrumentality on each car being connected up between said synchronizing and said negative lines.
